United States Patent Office.

JOHN WESLEY ALESWORTH, OF SANTA CRUZ, CALIFORNIA.

Letters Patent No. 72,581, dated December 24, 1867.

IMPROVEMENT IN BOXES FOR GAUGING SHINGLES.

The Schedule referred to in these Letters Patent and making part of the same.

TO ALL WHOM IT MAY CONCERN:

Be it known that I, JOHN WESLEY ALESWORTH, of Santa Cruz, county of Santa Cruz, State of California, have invented an Improved Gauging-Box for Shingles, &c.; and I do hereby declare the following description and accompanying drawings are sufficient to enable any person skilled in the art or science to which it most nearly appertains to make and use my said invention or improvements without further invention or experiment.

The object of my invention is to provide a gauging-machine for straightening and gauging the edges of lumber, such as boards, plank, and shingles, but more especially for gauging shingles after they have been split and shaved.

My invention consists of a platform mounted on legs, and having side boards with graduated steps at each end. A box of the desired length, with top and bottom removed, is placed upon the form between the side boards, and is provided with a transverse screen for pressing the shingles together. In order to bevel pieces of boards or plank, false bottoms are employed, having the necessary bevelled grooves. The false bottoms are raised by head-pieces having pins in them.

To more fully explain my invention, reference is had to the accompanying drawings and letters marked thereon, of which—

Figure 1 is a side sectional elevation taken through Y Y.

Figure 2 is a back view with the end removed.

Figure 3 is a side sectional elevation, showing the arrangement for tapering.

Figure 4 is an end view with the beveling-pattern in place.

A represents a form upon legs *a a*, having side boards *B B*. At the rear ends of these boards are formed graduated steps *b b b*; also, steps *b' b' b'* are made in the supplemental pieces *C' C'*, placed upon the inside of the boards at the front-end gauge. The box *D* is made of the desired length, and may be closed at both ends, the upper edges of which are lined with steel straps, *d d*, to prevent marring during the operation of planing or shaving. The apparatus may be stationed next the place of splitting and shaving, so as to be convenient, the shingles being partially sorted after shaving. They are selected and placed upon their edges in the box *D* until it is full, when the handle *E* is turned and the screen made tight, thus holding the shingles securely, when their upper edges may be shaved off. If the shingles are very narrow, one or more one-inch false bottoms may be put in until the upper edges of the shingles are at the required height. The box *D* may be six inches in depth, and will serve for shingles of that width for anything wider. The bar *F* is placed across the box *D*, and one end of the box *D* set upon it. The other stands upon the steps *b' b'*, as shown, any pair of the steps *b b*, and one end of the box *D* set upon it. The other stands upon the steps *b' b'*, as shown, thus raising the box to any desired height for the width required. The weights *e e e* or other device serve to keep the parts steady while shaving. If a tapering piece of wood or board is required, false bottoms, *G*, may be placed in the box until the depth of the box equals the greatest width of the desired piece. The pattern *H* is then placed upon one end of *G* and the board *I* laid upon this. The boards to be tapered are then locked into the box and the projecting upper edges shaved off. Fig. 4 shows the manner of beveling, which is done by placing the pattern *L* in the box upon the false bottom *K*. A small longitudinal slot is cut in this bottom so corresponding with the longest face of *L* as to be at right angles to it to receive the edge of the board *n* to be operated upon. This or any number of boards are then locked, as before, and the upper edges shaved or planed off, after which they may be turned over and the other edge finished. In this manner, by providing a number of patterns, a great variety of such work may be expeditiously done, the box being regulated in height and depth for the class of work to be done. For a shingle-gauge, where they are shaved by hand, it is a great labor-saver, as one man can gauge and pack much faster than could ordinarily be packed, while their value will be greater, because of their uniformity.

Having thus described my invention, what I claim, and desire to secure by Letters Patent, is—

A gauging-box for shingles, constructed with the sides *B*, with their graduated steps *b b b' b'*, together with the movable box *D* and bar *F*, substantially as and for the purpose described.

In witness whereof, I have hereunto set my hand and seal.

J. W. ALESWORTH. [L. S.]
